UNITED STATES PATENT OFFICE.

CHARLES ROWLAND, OF QUINCY, ILLINOIS.

POSTAL TABLET.

SPECIFICATION forming part of Letters Patent No. 367,163, dated July 26, 1887.

Application filed November 20, 1883. Serial No. 112,302. (No model.)

To all whom it may concern:

Be it known that I, CHARLES ROWLAND, of Quincy, in the county of Adams and State of Illinois, have invented a new and useful Improvement in Postal Tablets; and I do hereby declare that the following is a full and exact description of the same, reference being had to the accompanying drawings, and to the letters of reference marked thereon.

10 My invention relates to writing sheets or cards, which I designate as "postal tablets," and the novelty consists in the construction, arrangement, and adaptation of parts, as will be more fully hereinafter set forth, and specifically pointed out in the claims.

The device is preferably made of stiff paper or card-board, and the blank from which the device is formed is of approximate diamond shape. This diamond form assumes a rectangular form when the flaps are folded upon the body, and the lines of demarkation, where the folds are to be made, are formed by pressing in the material from opposite sides. When folded, the points of the flaps are adjacent to each other, while the edges of each flap lie close to the edges of the flaps adjacent. The points of the flaps are secured together by a gummed securing-flap, which may be formed either integral with one of the folding flaps 25 or in a separate piece to be attached thereto; or the flaps may be secured together by a separate gummed wafer.

The invention is fully illustrated in the accompanying drawings, which form a part of this specification, and in which—

Figure 1 is a diagram showing the blanks cut out of a sheet of proper material, with the securing-flap integral with one of the folding flaps of each tablet. Fig. 2 is a similar view 40 showing the blanks cut with a view to the employment of separate securing flaps or wafers, the points of all the flaps being adapted to lie close together at the center when the tablet is folded. Fig. 3 is a plan view of one 45 of the blanks, the folding-lines being shown in dotted lines. Fig. 4 is a similar view showing the device folded as an article of commerce; and Fig. 5 is an edge section, on an enlarged scale, of a part, showing the folding-line pressed 50 in from either side, compacting the material at that point to form a durable and strong hinge.

Referring to the drawings, in which similar letters of reference indicate like parts in all the figures, A designates the material of which the blanks B are cut, which material is preferably stiff paper or card-board. By suitable machinery the material is cut in the forms shown in Fig. 1—that is to say, with a gumming-flap, c, integral with one of the flaps b, 55 or in the form of a diamond, as shown in Fig. 2. Each blank when cut is composed of a body, D, and four folding flaps, b. The form of the blank is such that when the flaps are folded inward upon the body, and the edges of adjacent flaps lie close to each other, the folding-lines will describe the body as of rectangular form, and the points of all the flaps will be adjacent to each other at the center of the body. The blank at these folding-lines is 60 pressed inward from opposite sides to form a compressed hinge, as shown at f, Fig. 5, and to make the folding-lines apparent. This is done by appropriate machinery, and may be accomplished at the same operation with the 65 cutting.

When the device is in the form of a merchantable commodity, the flaps are folded upon the address side—that is to say, with the gummed side of the flap c outward, if that form 70 is employed.

The person using the tablet writes the message upon the exposed face, turns the flaps b, and seals the four points of the flaps together, after which he has only to write the address 75 upon the opposite side.

The important and essential features of the invention accrue to the construction and arrangement of the folding flaps, to the manner and means of securing the same when folded, 80 and in the formation of the folding-lines.

It will be observed that the lines f insure that the points of the flaps will come together at the center of the body, so that they may be properly secured together by the gumming-flap when the device is folded.

Having thus described my invention, what I claim as new, and desire to secure by Letters Patent of the United States, is—

1. A postal tablet, substantially as described, composed essentially of a body, D, and four flaps, b, the said flaps having a combined area equal to that of the body, and being so proportioned that when folded upon the 90

body in either direction the edge of one flap will abut against the edge of the adjacent flap, and their several points will meet at the center of the body, as set forth.

5 2. A postal tablet consisting of the body D, having folding flaps b, said flaps b having a combined area equal to that of the body, and one of the said flaps having integral therewith the gumming-flap c, substantially as set forth.

10 3. A postal tablet composed of a body, D,

the four folding flaps, as shown, and the folding-lines f, formed by pressing the material inward from opposite sides, substantially as set forth.

This specification signed and witnessed this 15
20th day of November, 1883.

CHARLES ROWLAND.
